UNITED STATES PATENT OFFICE.

MERLE M. NEWTON, OF COLORADO SPRINGS, COLORADO.

SEPARATOR.

Application filed April 18, 1922. Serial No. 554,433.

To all whom it may concern:

Be it known that I, MERLE M. NEWTON, a citizen of the United States, and a resident of Colorado Springs, in the county of El Paso and State of Colorado, have invented 5 certain new and useful Improvements in Separators, of which the following is a specification.

This invention relates to a separator.

10 The invention more particularly relates to an apparatus for separating a conglomerate of solids consisting in materials having different specific gravities such as found in mining operations for redeeming precious metals from sand and gravel beds or from 15 tailings of a mine or the like.

The invention has for its object to provide an apparatus whereby the different materials having different specific gravities may 20 be separated in a highly efficient manner.

Other objects will hereinafter appear.

In carrying out the invention there is employed three factors all of which operate to separate the materials of different specific 25 gravities, said factors being gravity, centrifugal force, and the specific gravities of the materials being separated. Preferably a pair of helical pans or tables are employed, said pans being concentric to each other and 30 turnable from a common means. Also each pan is inclined transversely viz, from its inner periphery upwardly and toward its outer periphery. The pans, in each instance, are also adjustable so that the end thereto 35 into which the material is deposited may be brought closer to the axis of rotation than the discharge end of said pan. Each pan separately operates for separation of materials. The pans are rotated and the material 40 in working its way toward the discharge end of each pan will be separated into different strata or zones; the outermost zone representing the material having the greatest specific gravity, the zone adjacent thereto representing the material having the 45 next greatest specific gravity, and so on, to the inner periphery of the pan.

The invention is illustrated by way of example in the accompanying drawings, in 50 which:—

Figure 1 represents a top plan view of the

separator constructed in accordance with the present invention.

Figure 2 is a similar view of one of the 55 pans and also showing in dotted lines the extreme position to which the pan may be moved.

Figure 3 is a vertical sectional view of the 60 pan shown in Figure 2 and the associated apparatus thereof.

Figure 4 is a top plan view of a modified 65 form of apparatus.

Referring to the drawings more particularly, in Figures 1 to 3 inclusive, P^1 and P^2 indicates generally the two helical pans, S generally indicates a shaft which is suitably supported at its lower end for rotation; and at B is generally indicated a receiving bin into which the materials after being divided or separated may be deposited. Upon the 70 shaft there is turnably mounted a pair of supporting members 10 and 11, the supporting member 10 being positioned above the member 11. Immediately below the supporting member 11 there is positioned a collar 12 adapted to hold the member 11 against downward movement, and above the supporting member there is loosely mounted upon the shaft S a cog wheel 13. A similar cog wheel 14 is likewise mounted upon the 75 shaft above the cog wheel 13 and is adapted to support the supporting member 10.

The pans P^1 and P^2 are supported by the members 10 and 11. Each pan is helical or spiral in formation and its inner surface 80 is arcuate in shape. Also each pan is provided with an outer retaining flange 16 and an inner retaining flange 17. Each pan is further formed with a projection or arm 18 by which the same is pivotally connected to the associated outer end of the lower support 11 by a bolt 19. Intermediate the supporting member 11 and the bottom of each pan there is interposed a bar 20 which is secured to the pan by a rivet 21 and the bolt 19 in the manner illustrated in Figure 3. The inner end of each bar 20 terminates in a rack bar 21 which is arcuate in shape and in constant mesh with the cog wheel 13.

There is also provided a bar 22 for each 100 pan which corresponds to the bar 20 having formed upon its inner end, in each instance,

an arcuate shaped rack bar 23 which is adapted to mesh with the cog wheel 14. The bar 22 is secured to the retaining flange 16 by a bolt as at 24 and in turn pivotally connected to the associated end of the supporting member 10 by a bolt 25.

The upper supporting member 10 is formed upon its one side with an arm or lug 26 in which there is mounted a crank 27, said 10 crank carrying a pinion 28 adapted to mesh with the cog wheel 14. As is obvious by this arrangement with the rotation of the pinion 28, the pans P^1 and P^2 may be swung upon their pivotal connections with the frame 15 members 10 and 11 and thus to adjust the distance between the ends of said pans and the supporting shaft S. In the lug 26 there may be provided a suitable opening to receive a pin 29 which may be extended into 20 openings 30 in the pinion 28 for locking the pinion in adjusted position.

As seen in Figure 1, the ends of the pan P^1 overlap the ends of the pan P^2 . Above the pans in any suitable position there may 25 be arranged a hopper H. This hopper may be supported in any suitable manner, not shown, and have a spout F extending therefrom to each of the pans P^1 and P^2 . The spout F in each instance should be distensible so that the same may be adjusted with 30 the pans, that is, with relation to the shaft S. The spout F for the pan P^1 is adapted to discharge material into the pan at a point adjacent its highest end and against 35 its upper peripheral edge, that is, at a point directly beneath the retaining flange 16. The spout F or pan P^2 discharges material into said pan at a similar point.

The bin B should consist in a plurality 40 of annular compartments as indicated at C, Figure 3. The outermost compartment is of such width that upon adjusting the pans with respect to the shaft S, the material discharged from a point adjacent the upper 45 edge of each pan will be at all times deposited in this compartment. The outermost compartment C will therefore receive the material having the greatest specific gravity. The compartment adjacent thereto will 50 receive the material having the next to the greatest specific gravity and the innermost compartment will receive the lightest material. The compartments C would correspond in number to the number of materials 55 having different specific gravities to be separated.

Referring to Figure 4, the pan P^3 is helical in form and constructed the same as the pans P^1 and P^2 with the exception that it is 60 of greater length. The pan P^3 makes a complete circle and its receiving end 30 being innermost and adapted to receive materials from the spout F' which communicates with the hopper H'. The discharging end 31 of 65 the pan is disposed over a bin B' which is

divided into different compartments C', each compartment representing a complete circle and adapted to receive a certain material separated in the pan P^3 .

In operating the present apparatus, the 70 shaft S may be manually rotated with a crank C² or with other power means.

The operation of the present apparatus is as follows: The material to be separated is dumped into the hopper H and from thence 75 will proceed into the upper ends of the pans P^1 and P^2 . The shaft S is preferably rotated in clockwise direction. As the materials proceed to move downwardly in each pan, so carried by gravity, the centrifugal force will 80 urge the materials having the greatest specific gravity toward the outer edge of the pan. The retaining flange 16 prevents the escape of this material.

The heaviest material which will occur 85 adjacent the outer edge of each pan will cling to the bottom of the pan and move longitudinally of the pan. The materials will separate themselves into different zones, the lighter materials moving toward the 90 shaft S and previous to the time of said materials reaching the discharge end of the pans they will be entirely separated in a uniform manner. The outermost zone as before stated will be composed of material having the 95 greatest specific gravity and the innermost zone of material being of the least specific gravity. The different materials will separately discharge into the compartments C 100 of the bin B.

It should be here mentioned that the material moves in the direction of rotation of the pans. As the material is deposited in the upper end of the pans as has been previously stated then the direction of rotation of the 105 pans would be clockwise. The stratification of the material begins immediately after the same has been deposited in the pans, that is, the heavier materials remain adjacent the outer edge of the pans and move longitudinally and downwardly while the lighter particles move longitudinally of the pans and also move inwardly toward the axis of rotation of the pans.

Furthermore by the pans rotating in a 110 direction similar to the movement of the material a greater amount of work is performed that is, due to the pans moving at a higher rate of speed than the flow of the material the surface of the pans oppose the movement 115 of the material and thus to cause a slower and more thorough stratification of the material.

From that heretofore recited it is believed 120 that if the pans would be rotated in an anti-clockwise direction and material deposited in the lower ends thereof, the said material would move upwardly and in a similar manner; the material then would be discharged from the upper end of the pans. 125 130

By an arrangement of this nature, a device of this character could be utilized for lifting material, that is, by rotating the pans in an anti-clockwise direction and permitting material to enter the lower ends thereof.

What I claim is:

1. In a separator of the character described, a helical shaped pan, means for supporting said pan for rotation upon its normal axis as a center, and means for adjusting the pan with relation to the axis of rotation.

2. In a separator of the character described, a helical shaped pan, means for supporting said pan for rotation upon its normal axis as a center, and means for adjusting the pan with relation to the axis of rotation, and means for locking the pan in its adjusted position.

3. In a separator of the character described, a helical shaped pan having a transversely curved surface, means for supporting the pan for rotation about its normal axis, and means for adjusting the pan with respect to said axis of rotation.

4. In a separator of the character described, a helical shaped pan, the ends of which are disposed substantially diametrically opposite each other, means for supporting the pan for rotation upon its normal axis, and means for adjusting the ends of said pan with relation to its axis of rotation.

5. In a separator of the character described, a vertical rotatable shaft, an arm extending from said shaft at right angles thereto, a helical shaped pan pivoted to said arm, means for swinging the helical pan upon its pivot with respect to the shaft, and means for rotating the shaft.

6. A separator of the character described comprising a vertical and rotatable shaft, an arm extending from said shaft at substantially right angles thereto, a helical shaped pan having its ends terminating in diametrically opposed relation, means for pivoting said pan upon the arm extending from said shaft, means for adjustably swinging the ends of said arm with relation to the shaft, and means for rotating said shaft.

7. A separator of the character described comprising a rotatable vertical shaft, an arm extending at right angles therefrom, a helical shaped pan arcuate in cross section with its outer peripheral edge elevated with respect to its inner peripheral edge and its ends being diametrically opposed, means for pivoting the pan upon said arm for swinging movement of its ends with relation to the shaft, means for locking the arm in adjusted position upon its pivot, and means for rotating said shaft.

8. In a separator, a helical shaped pan, means for supporting the pan to rotate about

its longitudinal axis, means whereby material to be separated may be deposited in the upper end of the pan adjacent its outer periphery, said pan being so shaped that with the downward travel of the material being separated the same will be formed into different strata or zones, the material of each zone or stratum having a different specific gravity.

9. In a separator of the character described, a helical shaped pan, means for supporting said pan to rotate about its longitudinal axis, said pan being of such a shape in cross section that upon material being fed into the upper end thereof and proceeding downwardly during the rotation of said pan said material will divide itself into different strata or zones, and the material of the inner zone or stratum being of a greater specific gravity than the materials in the other zones or strata.

10. In a separator of the character described, a helical shaped pan, means for supporting said pan to rotate about its longitudinal axis, said pan being of such a shape in cross section that upon material being fed into the upper end thereof and proceeding downwardly during the rotation of said pan said material will divide itself into different strata or zones, and the zone occurring nearmost the inner periphery of the pan having the greatest specific gravity, while different materials having less specific gravity arranging themselves progressively in zones toward the outer periphery of the pan.

11. In a separator of the character described, a helical shaped pan, means for supporting said pan to rotate about its longitudinal axis, said pan being of such a shape in cross section that upon material being fed into the upper end thereof and proceeding downwardly during the rotation of said pan said material will divide itself into different strata or zones, and the zone occurring nearmost the inner periphery of the pan having the greatest specific gravity, while different materials having less specific gravity arranging themselves progressively in zones toward the outer periphery of the pan, and means for depositing material into said pan at its upper end and adjacent the outer periphery thereof.

12. In a device of the character described, a helical pan, means for turnably supporting said pan to rotate upon its longitudinal axis with said axis disposed in a vertical plane, and means for shifting the rotative axis of said pan.

13. In a device of the character described, a helical shaped pan, means whereby said pan may be mounted to rotate about its longitudinal axis, said longitudinal axis being disposed in a vertical plane, said pan being so shaped that upon material having parti-

cles of different specific gravities being deposited in the upper end of the pan the same will separate into different zones or strata when proceeding toward the lower 5 end of the pan, and hoppers arranged beneath the lower end of the pan adapted to receive material leaving this end of the pan and maintain the separation thereof.

14. In a separator, a helical shaped pan, 10 means for supporting the pan to rotate about its longitudinal axis, means whereby

material to be separated may be deposited in the upper end of the pan adjacent its outer periphery, said pan being so shaped that with the downward travel of the material being separated that same will be formed into different strata or zones, the material of each zone or stratum having a different specific gravity, and means whereby the pan may be adjusted with respect to 15 its rotative axis.

MERLE M. NEWTON.
